UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,442, dated November 21, 1882.

Application filed August 11, 1882. Term of patent 3½ years.

To all whom it may concern:

Be it known that I, HENRY HORAN, of East Orange, in the State of New Jersey, have invented a new and original Design for Carpets, 5 of which the following is a specification.

This invention relates to a new and original design for carpets and similar fabrics; and it consists in the novel grouping and configuration of figures hereinafter more fully described.

10 The accompanying photograph illustrates a face view of a carpet having my new design.

The blank field *a* appears between the large flower groups. The blank field *b* mostly underlies the large flower groups and projects out 15 over the field *a* in various irregular coral or lichen-like forms following in great part the sprays from the large flower-groups.

A is a large flower-and-leaf group, having 20 large open roses and circular flowers at its center resting on a mass of leaves, above and to the left a group of small circular flowers and leaves, and a similar group to the right and above, and below and on all sides jutting fern sprays and

leaf-clusters. The group *B* is a flower-and-leaf group, having at its left an interlocking net-work or arbor-work of branches. *C* is a flower-and-leaf group, having a similar net-work of branches on its right. Scattered over the rest of the ground are various smaller groups and clusters of flowers and leaves, as shown in the 30 accompanying photograph.

I claim—

1. The design for carpets, consisting of the grounds *a* and *b*, substantially as shown.
2. The design for carpets, consisting of the 35 groups *A*, *B*, and *C*, and the intervening smaller groups, substantially as shown.
3. The design for carpets, consisting of the groups *A*, *B*, and *C*, and the intervening smaller groups, and the grounds *a* and *b*, substantially 40 as shown and described.

HENRY HORAN.
